(57) CLAIM

The ornamental design for iron golf club head, as shown and described.

DESCRIPTION

FIG. 1 is a perspective rear view of my new design for an iron golf club head;

FIG. 2 is a rear elevational view thereof;

FIG. 3 is a front elevation view thereof;

FIG. 4 is a bottom plan view thereof;

FIG. 5 is a toe end view thereof;

FIG. 6 is a heel end thereof; and,

FIG. 7 is top plan view thereof.

The broken lines shown are included for the purpose of illustrating unclaimed subject matter and form no part of the claimed design.
